UNITED STATES PATENT OFFICE.

FREDRIC C. WEIR, OF CINCINNATI, OHIO.

SPRING-FROG.

SPECIFICATION forming part of Letters Patent No. 409,539, dated August 20, 1889.

Application filed March 30, 1889. Serial No. 305,465. (No model.)

To all whom it may concern:

Be it known that I, FREDRIC C. WEIR, a citizen of the United States, and a resident of Cincinnati, in the county of Hamilton and State of Ohio, have invented certain new and useful Improvements in Spring-Frogs, of which the following is a specification.

My invention relates to an improvement in spring-frogs, the object of which is to provide a strengthening-piece which, in connection with the holding-down device, will prevent the spring-frog from rising, and supporting it in its movement, the various features of which will be fully set forth in the description of the accompanying drawings, making a part of this specification, in which—

Figure 1 is a top plan view partly in section, showing my improvement in spring-frogs. Fig. 2 is a side elevation showing a modification, the rail and strengthening-bar being broken away; and Fig. 3 is a detail side elevation of the construction shown in Fig. 1.

1 2 represent the main rails of the frog; 3 4, the point-rails. Rail 1 is the movable wing-rail, which is moved forward against the tension of spring 6 by the flange of car-wheels, and the recoil of spring forces the rail back after the train has passed.

Great difficulty has been experienced in the breaking of spring-rails and of their rising and creeping-in action. My improvement overcomes this objection by means of the strengthening-bar 7, that reaches from the rear of the base-plate of the frog forward beyond the throat, which is the point of greatest strain. This filling-piece is secured to the flange of the rail by bolts or rivets 8. It is shaped to fit the contour of the rail and

bent to correspond with the taper or angle of the said frog.

9 represents an arm welded to the strengthening-arm 7. 10 represents parallel arms hinged thereto by bolt 11.

12 represents a filling-block which keeps the arms 10 apart sufficient to allow them to turn freely over the arms 9 and 14. The forward ends of said arms are hinged by bolt 13 to the arm 14, which is preferably bent round under the base-plate, passing through a slot cut in the same, and secured by the pivot-bolt 13.

In the modification shown in Fig. 2 the arm 14 is prolonged above the plate and secured to the top side thereof by means of rivets 16. The said arm 14, being rigid, furnishes a strong support to the pivot 13, on which the link-arms 10 journal at one end, the other journaling on the arm 9. By means of this arm 9 secured to the strengthening-bar 7 the rail is held vertical to the base-plate and allowed to move outward freely under the strain of the train.

Having described my invention, what I claim is—

The combination, with a railway-frog, of 65 the stiffening-bar 7, rigidly secured to the web of the moving rail and provided with an arm 9 hinged to the link 10 and to the bar 14, secured to the base-plate, substantially as specified.

In testimony whereof I have hereunto set my hand.

FREDRIC C. WEIR.
